DESIGN FOR A STORE BUILDING

Anthony W. Vanderput, Los Angeles, Calif.

Application March 14, 1939, Serial No. 83,571

Term of patent 14 years

To all whom it may concern:

Be it known that I, Anthony W. Vanderput, a subject of the Kingdom of Holland, residing at Los Angeles, State of California, have invented a new, original, and ornamental Design for a Store Building, of which the following is a specification, reference being had to the accompanying drawing, forming a part thereof.

In the drawing:

I claim:

The ornamental design for a store building, as shown.

ANTHONY W. VANDERPUT.
